WATCH AND TIMEPIECE

Rolf Woldemar Hering, Rio de Janeiro, Brazil

Application June 26, 1940, Serial No. 342,433
In Brazil July 26, 1939

1 Claim. (Cl. 58—85)

This invention relates broadly to watches and clocks and, more particularly, to an improvement in the structure for winding the same.

One object is to provide a structure for winding a timepiece, and to provide, along with the winding structure, means for ascertaining, at any time, the amount of time for which the timepiece will run until re-winding is necessary,

Another object is the provision of a winding mechanism for timepieces which will provide for the rapid winding of such timepiece with slight effort, and which eliminates the milled stem or knob heretofore almost universally used in watches and similar timepieces. At the same time it is intended to provide a device which may be applied to the basic structure of certain timepieces now in existence without extensive modification of such basic structures.

Still again it is an object to avoid the possibility of breakage of the main spring of the timepiece resulting from excessive winding. In the furtherance of this object it is now proposed to provide means which will prevent winding beyond certain predetermined limitations.

The invention is illustrated in the following specification and drawing in which

Figure 1 is a plan view;

Figure 2 is a side elevation;

Figure 3 is a fragmentary section; and

Figure 4 is a diagrammatic plan of the gearing.

Referring now to the drawing, in which like reference numerals denote similar elements, the invention is embodied in a watch comprising a main casing 2 which encloses an inner mechanism including a stem 4, gearing 6 driven by rotation of the stem for winding the main spring 8 which in turn drives hands 10 through suitable mechanism. The inner workings of the timepiece form no part of this invention and are merely illustrative of the type of device to which the invention is applicable.

The inventive structure comprises a pinion 12 fixed to stem 4 for rotation therewith, it being noteworthy that stem 4 does not have the usual knurled external winding element. Rotatively mounted in casing 2 is a ring 14, a segment of which is provided with gear teeth 16 on the edge thereof which lies within the main casing. Gear teeth 16 mesh with pinion 12 on stem 4 so that, as ring 14 is turned relative to casing 2, pinion 12 is thereby rotated so as to turn the

stem 4 to wind the watch. In the example shown, rotation of ring 14 counterclockwise winds the watch. While the particular gearing and winding mechanism selected is not critical, it is a further feature of the invention that the gearing be such that as the watch runs down, the stem 4 rotates to drive ring 14 in a clockwise direction.

Ring 14 is provided, on its exposed edge, with a pair of stops 18 and 20 angularly spaced from one another a distance equal to the angular extent of gear teeth 16, an abutment 22 in the form of a pointer being affixed to main casing 2 between the stops so that, when ring 14 is rotated counterclockwise, stop 18 engages abutment 22 when the end of the series of gear teeth 16 reaches pinion 12, in which position the watch is wound. When the watch is unwound, ring 14 will have rotated to bring stop 20 against abutment 22.

Of particular importance is the provision of graduations 24 spaced along ring 14 between stops 18 and 20 so that it may be determined by inspection to what extent the watch is wound and to what extent the watch will run until it will need further winding. Preferably the graduations lie so that they may be associated with abutment 22 which forms a pointer. It is to be understood that while the invention was illustrated as applied to a watch, it is likewise applicable to other timepieces such as alarm clocks, and other horological instruments.

Having thus described in detail the invention and the method of realization of same, I claim:

A watch or other timepiece having means indicating the extent to which the watch is wound, comprising a toothed member within the watch case, a stem actuated by said member for transmitting a rotary motion to the spring winding mechanism of the watch, an actuating ring member forming part of the sidewall of the watch case, and internal arcuate series of teeth formed on said ring and meshing with said toothed member to wind the watch, said indicating means further comprising members respectively on the ring and on the other part of the sidewall of the watch case, and stops for limiting the movement of said ring at the fully wound and unwound positions of the spring.

ROLF WOLDEMAR HERING.
